LOCK

Mathew Schnur, Chicago, Ill.

Application October 9, 1944, Serial No. 557,885

9 Claims. (Cl. 292—340)

This invention, relates, in general, to locks, and has particular relation to an improved form of door lock of the type having a dead-bolt operated by a key, combination, knob, or the like.

In the usual dead-bolt type of lock the bolt must be actuated to retracted position, for example, by a key, combination, knob, or the like, to permit the door to be closed. Then upon closing the door the key, combination, knob, or the like must be manipulated to move the bolt to extended position engaging in the opening in the door jamb in order to lock the door in closed position.

One of the main objects of the present invention is to provide an improved form of dead-bolt lock in which the bolt need not be withdrawn to permit the door to be closed, and thereafter actuated to extended position to lock the door closed. In other words, the door is adapted to be closed with the dead-bolt in extended position and without withdrawal of the bolt from such position, and when the door reaches closed position the bolt is effective to lock it in such position.

Another object of the invention is to provide a locking plate on the door jamb which stays in released position until the bolt reaches substantially its locking position, and then operates into locking engagement with the extended bolt to lock the door or the like closed.

Another object of the invention is to provide in conjunction with a bolt and locking plate of the class described, an actuating member which, by cooperation with the extended bolt as it reaches locking position, actuates the locking plate into locking engagement with the extended bolt.

Another object of the invention is to provide means which is operable into locking engagement with the locking plate to lock the same against being pushed back to released position, or otherwise tampered with, or surreptitiously released when the locking plate is in locking engagement with the bolt.

Another object of the invention is to provide a lock of the class described having various features of novelty and advantages, and which is particularly characterized by its effectiveness and security in use, its simplicity in construction, its economy in manufacture, and its adaptability for use with any lock in which the bolt is not withdrawn, for example, by closing of the door.

Further objects and advantages of the invention will appear from the following detailed description, taken in connection with the accom-

panying drawing which illustrates the manner of constructing and using a lock embodying the present invention.

In the drawing:

Figure 1 is a fragmentary view showing a portion of the outer side of a door and its cooperating jamb, and also showing a lock embodying the present invention applied thereto;

Figure 2 is a fragmentary sectional view taken substantially on the line 2—2 of Figure 1;

Figure 3 is an elevational view of the lock mechanism applied to the door jamb, with the cover removed and looking from the inner side thereof;

Figure 4 is a sectional view taken substantially on the line 4—4 of Figure 3;

Figure 5 is a sectional view taken substantially on the line 5—5 of Figure 3;

Figure 6 is a fragmentary detail view showing one form of means for anchoring one end of the spring element through which the locking plate is actuated into locking engagement with the bolt by the actuating member operated by the bolt;

Figure 7 is a detail elevational view showing the actuating member which is actuated by the bolt and operates the locking plate into locking engagement with the bolt and the finger carried thereby for releasing the means which locks the locking plate in locking position; and

Figure 8 is another view of the actuating member and finger shown in Figure 7, taken at right angles and from the right as these members are viewed in Figure 7.

Referring now to the drawing, a door is shown fragmentarily at 10, and its cooperating jamb is shown fragmentarily at 11.

The dead-bolt 12 on the door 10 is shown in extended position. It is moved to extended and retracted positions by mechanism under the control, for example, of a key, combination, knob or the like. This latter mechanism per se forms no part of the present invention, and therefore has not been shown or described.

The lock of my present invention comprises an angular bracket 15 attached to the door jamb 11 and provided at the inner corner thereof with an opening 16 which is adapted to receive the extended bolt 12 upon movement of the door 10 to closed position. A locking plate 17 is pivoted at 18 to the inner side of one leg of the bracket 15. An actuating member 19 is pivoted at 20 to the inner side of the other leg of the bracket 15. The actuating member 19 has a detent release mem-

ber 21 fixed to the member 19 for swinging movement with the member 19 about its pivot 20.

A link 22, pivoted at 23 to the inner housing or guard 24, has an outstanding lug 25. A second link 26 is pivoted at 27 to the link 22, and at 28 to the member 21. A coiled tension spring 29 is connected between the lug 25 and a lug 30 struck out, for example, from the inner housing or guard 24. This spring 29 normally holds the actuating member 19 in its dotted line position *a* (Figure 3). With the member 19 in the dotted line position *a*, the nose 31, at its free end, is positioned in the opening 16 adjacent the inner surface of the jamb 11 so that upon movement of the door 10 to closed position, with the bolt 12 extended, the extended bolt 12 will engage the nose 31 of the actuating member 19 and swing this member 19 counterclockwise (Figure 3) about its pivot 20 to the dotted line position *b*.

A second coiled tension spring 32 is connected between the lug 25 and a lug 33 on the locking plate 17. As the actuating member 19 is swung counterclockwise (Figure 3) by engagement of the extended bolt 12 therewith, the detent release member 21 moves toward its full line position as shown in this figure, raising the link 23 to its full line position through the link 26. In the accompanying upward movement of the lug 25, the spring 32 actuates the locking plate 17 clockwise (Figures 4 and 5) about its pivot 18 from released position, as shown in Figure 4, into locking engagement in front of the bolt 12, as shown in Figure 2, to lock the door in closed position.

The spring connection at 32 preferably has sufficient lost motion therein so that the locking plate 17 will remain in released position until the bolt 12 is in locking position or in position to permit engagement of the locking plate 17 with the bolt 12 as shown in Figure 2. The locking plate 17 is held yieldingly in released position and returned to this position by a coiled tension spring 35 connected, for example, between a pin 36 on the locking plate 17 and a lug 37 on the adjacent leg of the bracket 15.

The locking plate 17 adjacent its free end has a notch forming a shoulder 38 which, upon movement to locking position, engages behind the adjacent leg of a detent 40 pivoted at 41 to the adjacent leg of the bracket 15. The detent 40 is yieldingly urged to its locking position by a coiled tension spring 42 connected between the detent 40 and a lug 43 on the bracket 15. As the locking plate 17 swings to locking position the detent 40 snaps over the adjacent end of the plate 17 and into locking engagement with the shoulder 38 to lock the plate 17 against being pressed back or surreptitiously released or otherwise tampered with as long as it is in locking position.

The detent release member 21 has a projecting finger 45 which, by cooperation with the other leg of the detent 40, swings the detent counterclockwise (Figure 4) about its pivot 41 to released position by the movement imparted to the actuating member 19 by the extended bolt 12 in moving the door 10 to closed position. The inner housing or guard 24 is secured in place, for example, to a spacer 48 by screws 48, the spacer being secured to the bracket 15. The guard 24 has an angular lug 49 positioned in juxtaposition to the detent 40, for example, to hold the detent 40 against displacement from its pivot 41 and also to hold the locking plate 17 in place for swinging movement on its pivot.

The front plate of the lock on the door 10 has a leg 50 forming a safety or guard plate for cov-

ering the outer side of the opening 16 when the door is closed. This is particularly suitable where the opening 16 is on the outer side of the jamb 11. Where the opening 16 is on the inner side of the jamb, the bracket or guard plate 50 may be omitted. An inner angular cover is preferably provided as shown at 52 in Figure 2.

The lock operates, in general, as follows:

With the door 10 in open position the locking plate 17 is held by the spring 35 in the released position shown in dotted lines toward the left hand side of the device as it is viewed in Figure 4. The actuating member 19 is held in its position *a*, as shown in Figure 3, by the spring 29, and the spring 42 holds the detent 40 yieldingly in the position shown in full lines in Figure 4.

As the door 10 is closed with the bolt 12 in extended position, the bolt engages the nose 31 of the actuating member 19 and swings this member counterclockwise about its pivot 20 from position *a* toward position *b*. The lost motion in the spring connection 32 permits the actuating member 19 to move free of the locking plate 17, or relatively free of this plate, until the extending end of the bolt 12 is in position to permit the locking plate 17 to swing into locking engagement in front of the bolt 12, as shown in Figure 2. When the bolt 12 is in position to permit locking engagement of the locking plate 17 therewith, the spring connection 32 acts to swing the locking plate 17 clockwise (Figure 4) about its pivot 18 and into locking engagement with the bolt as shown in Figure 2 by the swinging movement of the actuating member 19. The door 10 is then locked in closed position, and, where bracket 50 is employed, this bracket is positioned as shown in Figure 2.

As the locking plate 17 reaches locking position, its free end snaps past the adjacent leg of the detent 40, which detent springs into locking engagement with the shoulder 38 under the action of the spring 42. The engagement of the detent 40 with the shoulder 38 locks the plate 17 against being pushed back to released position or against being surreptitiously released or otherwise tampered with.

When authorized opening of the door is desired, the key, combination, knob or the like is manipulated to withdraw the bolt 12 to retracted position. The door 10 may then be swung to open position, whereupon the actuating member 19 is swung to its dotted line position *a* as shown in Figure 3. In this swinging movement of the actuating member 19, the finger 45 thereon swings the detent 40 to released position as shown in dotted in Figure 4, and the locking plate 17 swings to its released position, as shown in dotted lines in Figure 4, under the action of the spring 35.

The embodiment of the invention shown in the drawing is for illustrative purposes only, and it is to be expressly understood that said drawing and the accompanying specification are not to be construed as a definition of the limits or scope of the invention, reference being had to the appended claims for that purpose.

I claim:

1. In a lock of the class described, in combination, an angular bracket adapted to be applied to a door jamb and having an opening at the corner thereof adapted to receive an extended bolt on a door upon movement of the door to closed position, a locking plate pivoted to the inner side of one leg of said bracket and normally held in released position, an actuating member pivoted to the inner side of the other leg of said bracket

and normally held in position to cooperate with and be actuated by the extended bolt in its movement to locking position, and means interconnecting said actuating member and said locking plate for actuating said locking plate into locking engagement with the bolt by the actuation of said actuating member by cooperation of the extended bolt therewith.

2. In a lock of the class described, in combination, an angular bracket adapted to be applied to a door jamb and having an opening at the corner thereof adapted to receive an extended bolt on a door upon movement of the door to closed position, a locking plate pivoted to the inner side of one leg of said bracket and normally held in released position, an actuating member pivoted to the inner side of the other leg of said bracket and normally held in position to cooperate with and be actuated by the extended bolt in its movement to locking position, and means interconnecting said actuating member and said locking plate for actuating said locking plate into locking engagement with the bolt by the actuation of said actuating member by cooperation of the extended bolt therewith, said last means having lost motion therein so that said locking plate will remain in released position until the bolt is in substantially locking position and will be actuated into locking engagement with the bolt as it reaches substantially its locking position.

3. In a lock of the class described, in combination, an angular bracket adapted to be applied to a door jamb and having an opening at the corner thereof adapted to receive an extended bolt on a door upon movement of the door to closed position, a locking plate pivoted to the inner side of one leg of said bracket and normally held in released position, an actuating member pivoted to the inner side of the other leg of said bracket and normally held in position to cooperate with and be actuated by the extended bolt in its movement to locking position, means interconnecting said actuating member and said locking plate for actuating said locking plate into locking engagement with the bolt by the actuation of said actuating member by cooperation of the extended bolt therewith, said last means having lost motion therein so that said locking plate will remain in released position until the bolt is in substantially locking position and will be actuated into locking engagement with the bolt as it reaches substantially its locking position, and means operable into locking engagement with the locking plate to lock said plate against being surreptitiously released or otherwise tampered with when the locking plate is in locking engagement with said bolt.

4. In a lock of the class described, in combination, an angular bracket adapted to be applied to a door jamb and having an opening at the corner thereof adapted to receive an extended bolt on a door upon movement of the door to closed position, a locking plate pivoted to the inner side of one leg of said bracket and normally held in released position, an actuating member pivoted to the inner side of the other leg of said bracket and normally held in position to cooperate with and be actuated by the extended bolt in its movement to locking position, means interconnecting said actuating member and said locking plate for actuating said locking plate into locking engagement with the bolt by the actuation of said actuating member by cooperation of the ex-

tended bolt therewith, said last means having lost motion therein so that said locking plate will remain in released position until the bolt is in substantially locking position and will be actuated into locking engagement with the bolt as it reaches substantially its locking position, means operable into locking engagement with the locking plate to lock said plate against being surreptitiously released or otherwise tampered with when the locking plate is in locking engagement with said bolt, said last means comprising a detent having a spring for actuating same to locking position, and means on said actuating member for releasing said detent upon withdrawal of the bolt from locking engagement with said locking plate.

5. In a lock of the class described, in combination, an angular bracket adapted to be applied to a door jamb and having an opening at the corner thereof adapted to receive an extended bolt on a door upon movement of the door to closed position, a locking plate pivoted to the inner side of one leg of said bracket, a spring connected between said locking plate and means on said bracket for normally holding said plate in released position, an actuating member pivoted to the inner side of the other leg of said bracket, a spring connected between said actuating member and means on said bracket and normally holding said actuating member in projected position in the bolt receiving opening in said bracket to cooperate with and be actuated by the extended bolt in its movement to locking position, and a spring connection between said actuating member and said locking plate for actuating said locking plate into locking engagement with the bolt by the actuation of said actuating member by cooperation with the extended bolt.

6. In a lock of the class described, in combination, an angular bracket adapted to be applied to a door jamb and having an opening at the corner thereof adapted to receive an extended bolt on a door upon movement of the door to closed position, a locking plate pivoted to the inner side of one leg of said bracket, a spring connected between said locking plate and means on said bracket for normally holding said plate in released position, an actuating member pivoted to the inner side of the other leg of said bracket, a spring connected between said actuating member and means on said bracket and normally holding said actuating member in projected position in the bolt receiving opening in said bracket to cooperate with and be actuated by the extended bolt in its movement to locking position, and a spring connection between said actuating member and said locking plate for actuating said locking plate into locking engagement with the bolt by the actuation of said actuating member by cooperation with the extended bolt, said last spring connection having lost motion therein so that said locking plate will remain in released position until the bolt is in substantially locking position and will be actuated into locking engagement with the bolt as it reaches substantially its locking position.

7. In a lock of the class described, in combination, an angular bracket adapted to be applied to a door jamb and having an opening at the corner thereof adapted to receive an extended bolt on a door upon movement of the door to closed position, a locking plate pivoted to the inner side of one leg of said bracket, a spring connected between said locking plate and means on said bracket for normally holding said

plate in released position, an actuating member pivoted to the inner side of the other leg of said bracket, a spring connected between said actuating member and means on said bracket and normally holding said actuating member in projected position in the bolt receiving opening in said bracket to cooperate with and be actuated by the extended bolt in its movement to locking position, a spring connection between said actuating member and said locking plate for actuating said locking plate into locking engagement with the bolt by the actuation of said actuating member by cooperation with the extended bolt, a detent pivoted to the inner side of the leg of the bracket to which said locking plate is pivoted, a spring connected between said detent and means on said bracket for actuating said detent into locking engagement with the locking plate to lock said plate against being surreptitiously released or otherwise tampered with when the locking plate is in locking engagement with said bolt, and a finger on said actuating member for releasing said detent from said locking plate upon withdrawal of the bolt from locking engagement with said plate.

8. In a lock of the class described, in combination, an angular bracket adapted to be applied to a door jamb and having an opening at the corner thereof adapted to receive an extended bolt on a door upon movement of the door to closed position, a locking plate pivoted to the inner side of one leg of said bracket, a spring connected between said locking plate and means on said bracket for normally holding said plate in released position, an actuating member pivoted to the inner side of the other leg of said bracket, a spring connected between said actuating member and means on said bracket and normally holding said actuating member in projected position in the bolt receiving opening in said bracket to cooperate with and be actuated by the extended bolt in its movement to locking position, a spring connection between said actuating member and said locking plate for actuating said locking plate into locking engagement with the bolt by the actuation of said actuating member by cooperation with the extended bolt, a detent pivoted to the inner side of the leg of the bracket to which said locking member is pivoted, a spring connected between said detent and means on said bracket for actuating said detent into locking engagement with the locking plate to lock said plate against being surreptitiously released or otherwise tampered with when the locking plate is in locking engagement with said bolt, a finger on said actuating member for releasing said detent from said locking plate upon withdrawal of the bolt from locking engagement with said plate, inner guard means carried by said bracket and having a lug in juxtaposition to said detent for preventing displacement of the detent from its pivot, and linkage means comprising links pivoted to said inner guard, to said finger, and to each other for actuating said actuating member and said finger by said second spring.

5 to lock said plate against being surreptitiously released or otherwise tampered with when the locking plate is in locking engagement with said bolt, a finger on said actuating member for releasing said detent from said locking plate upon withdrawal of the bolt from locking engagement with said plate, and inner guard means carried by said bracket and having a lug in juxtaposition to said detent for preventing displacement of the detent from its pivot.

10 9. In a lock of the class described, in combination, an angular bracket adapted to be applied to a door jamb and having an opening at the corner thereof adapted to receive an extended bolt on a door upon movement of the door to closed position, a locking plate pivoted to the inner side of one leg of said bracket, a spring connected between said locking plate and means on said bracket for normally holding said plate in released position, an actuating member pivoted to the inner side of the other leg of said bracket, a spring connected between said actuating member and means on said bracket and normally holding said actuating member in projected position in the bolt receiving opening in said bracket to cooperate with and be actuated by the extended bolt in its movement to locking position, a spring connection between said actuating member and said locking plate for actuating said locking plate into locking engagement with the bolt by the actuation of said actuating member by cooperation with the extended bolt, a detent pivoted to the inner side of the leg of the bracket to which said locking member is pivoted, a spring connected between said detent and means on said bracket for actuating said detent into locking engagement with the locking plate to lock said plate against being surreptitiously released or otherwise tampered with when the locking plate is in locking engagement with said bolt, a finger on said actuating member for releasing said detent from said locking plate upon withdrawal of the bolt from locking engagement with said plate, inner guard means carried by said bracket and having a lug in juxtaposition to said detent for preventing displacement of the detent from its pivot, and linkage means comprising links pivoted to said inner guard, to said finger, and to each other for actuating said actuating member and said finger by said second spring.
